UNITED STATES PATENT OFFICE.

WILLIAM F. POLSON, OF BUFFALO, NEW YORK.

WIND-SHIELD.

1,215,407.

Specification of Letters Patent. Patented Feb. 13, 1917.

Application filed October 27, 1913. Serial No. 797,545.

To all whom it may concern:

Be it known that I, WILLIAM F. POLSON, a citizen of the United States, residing at Buffalo, in the county of Erie and State of New York, have invented certain new and useful Improvements in Wind-Shields, of which the following is a specification.

My invention relates to improvements in wind-shields and more particularly to that 10 foldable class used for motor road vehicles.

The primary object of my invention is the production of a simple and inexpensive shield of this type in which two sections or panels are employed and so arranged and attached that full protection may be had from the elements of the weather; yet, when desired, the sections or panels may be swung to obtain an unobstructed view of the road and at the same time protect the rider from 20 rain; also permitting of other adjustments, as occasion may require.

Another object of my invention is the provision of a shield in which the sections or panels are supported in a manner permitting of adjustments hitherto not known, 25 whereby the various weather positions can be obtained in a simplified manner and a shield produced having all advantages at a greatly reduced price.

30 A further object is to provide a self closing joint between the shield proper and the dash board which will effectually prevent drafts and also guard against the admission of water at this point.

35 With these and other objects in view my invention consists in the relative and simplified arrangement of the sections or panels and their connections whereby they may be easily and quickly adjusted to different 40 weather positions; in the novel joint closure between the shield proper and the dash board; and in the arrangement, construction, and combination of parts to be hereinafter described and particularly pointed out in 45 the subjoined claims.

In the drawings,

Figure 1 is a front elevation of a wind-shield embodying my invention.

Fig. 2 is an enlarged vertical section taken 50 on line 2-2, Fig. 1.

Fig. 3 is an edge elevation showing the upper section or panel and its supporting frame-section lowered to reduce the height of the shield.

55 Fig. 4 is a similar elevation with the up-

per and lower sections or panels swung at an angle.

Similar numerals of reference refer to similar parts in the several figures.

The reference numeral 5 designates a part 60 of an automobile, 6 the dash-board thereof including the filler-board, 7, and 8 the engine hood.

Rising from the dash-board or some other fixed part of the automobile are two standards or supports 9, which may be braced in any suitable manner, such as by means of the braces 10 extending forwardly and downwardly therefrom for connection with their forward or lower ends to the frame of 70 the automobile, or by other approved means.

The upper ends of the standards or supports 9 are flattened and preferably offset rearwardly, as at 11, and to said flattened ends are pivotally connected the lower similarly flattened rearwardly offset ends of a pair of arms 12, one arm being connected to each standard or support.

The filler-board 7, as stated, may be considered a part of the dash-board and secured 80 thereto is a weather guard 13 constructed of flexible and compressible material. The filler is invariably provided for the reason that the lower edge of the wind shield proper is straight-lined and the cowls or 85 dash-boards of automobiles are invariably formed otherwise than straight lined so that it is necessary to interpose an element between the cowl or dash-board and the wind-shield, but in a broad sense this filler board 90 does not form a part of the wind-shield but rather a part of the cowl or dash-board. This guard is in the form of a strip and on its underside has two depending marginal flanges 14 which form a shallow channel 95 into which the upper edge of the filler-board is fitted. On its upper side said guard or strip has a rib 15 along its rear marginal portion and a comparatively high web 16 along its front marginal portion, said web 100 16 yielding under pressure in a forward direction and recovering itself when pressure ceases. Between the rib 15 and web 16 a metallic strip 17 is placed through which and the guard, screws 18 or other suitable 105 securing means are passed that take into the filler-board. In cases where no filler-board is employed, the guard is secured to the dash-board proper.

The wind-shield has two sections or pan-

110

els 19, 20, one an upper section and the other a lower. Each of said sections comprises a U-shaped frame 21 and a pane of glass 22 or any other suitable material, the frame of 5 the lower section or panel having its lower corners preferably square while the upper corners of the upper section or panel are rounded. The lower edge of the upper pane of glass and the upper edge of the lower pane 10 abut or almost abut and cross bars which would obstruct the view are therefore dispensed with at this point.

Secured to the upper ends of the sides of the lower U-shaped frame 21 are brackets 23, 15 the upper ends of which are pivotally attached to the upper ends of the standards or supports 9, each of the latter being positioned between one of said brackets and one of the arms 12. The pivotal points of said 20 arms and the lower section or panel 20 are therefore coincident and it is to be noted that the axes of the two are alined with the joint between the upper and lower sections or panels 19, 20.

25 The upper section or panel has bosses 24 extending outwardly from its side bars, preferably at a point nearer its upper edge than its lower and these bosses are pivotally connected to the upper ends of the arms 12.

30 The means employed for pivotally securing the sections or panels 19, 20, and the arms 12, may be any of the common means usually employed in wind-shields, in the construction of which provision is made for 35 maintaining the sections or panels and the arms in alinement in parallel relation, or at any desired angle to their supporting members.

It is to be noted that the lower horizontal 40 bar of the lower U-shaped frame 21 fits between the rib 15 and the web 16 of the guard strip and bears against the latter, flexing the same so as to insure positive contact along the entire length of the lower 45 section, thus making a weatherproof joint at this point.

Either section or panel may be swung independent of the other, the lower swinging inwardly for ventilating purposes and the 50 upper swinging outwardly or inwardly, as desired. The upper section may also be swung inwardly and downwardly with its supporting arms so that it hangs parallel with and in rear of the lower section, as 55 shown in Fig. 3. By reversing the windshield on its supports or standards, a re-

verse action of the sections is obtained. When the lower section or panel is swung inwardly for ventilating purposes the continuity of the shield is not broken, since the 60 upper edge of the lower panel or section and the lower edge of the upper panel or section remain in substantially the same relation as when the lower section or panel is in line with the upper section or panel. This is a 65 decided advantage of my invention since it protects the occupants of the automobile while properly ventilating the same.

Having thus described my invention, what I claim is,—

1. In combination with the dash-board, a yielding strip secured to the upper edge thereof and having a rear marginal rib along its upper face and a forward marginal web also along its upper face, and a panel pivotally secured to a suitable support and having its lower edge bearing against said rib and web.

2. In combination with the dash-board, a yielding strip having a channel on its under 80 side to receive the upper edge of said dash-board and a rib and web at its upper side extending along opposite marginal portions, supports extending upwardly at opposite 85 ends of said dash-board, and a panel pivotally attached at its upper end to said supports and having its lower edge in contact with said rib and web.

3. In combination with a fixed member, supports at opposite ends of said fixed member, a transparent member normally alined with said fixed member and pivotally attached to said supports, and a weather guard secured to one of said members, said guard having a rib and web on its exposed face 90 along opposite marginal portions against which the other member bears.

4. In combination with a fixed member, a yielding strip having a rib and a web at its upper side extending along opposite marginal portions thereof, a metallic strip between said rib and web, means for fastening said yielding strip and said metallic strip to said fixed member, and a panel pivotally supported and having one of its edges in 10 contact with said web.

In testimony whereof I affix my signature in presence of two witnesses.

WILLIAM F. POLSON.
